UNITED STATES PATENT OFFICE.

RICHARD S. SARVER, OF CHICAGO, ILLINOIS.

ALARM CLOCK.

Application filed January 12, 1924. Serial No. 685,769.

To all whom it may concern:

Be it known that I, RICHARD S. SARVER, a citizen of the United States, and a resident of the city of Chicago, county of Cook, and 5 State of Illinois, have invented certain new and useful Improvements in Alarm Clocks, of which the following is a specification.

My invention relates to new and useful improvements in alarm clocks, and has for 10 its object, in general, the provision of means to assure the proper manipulation and operation of the alarm device under various condition of the time and alarm mechanisms of said clock.

15 A particular object of the invention is to provide means for automatically locking the alarm setting and timing mechanism and prevent changing or setting thereof while the alarm lever is in its "off" position with the alarm shut off, and to provide means for releasing said locking means when said lever is returned to its "on" position.

Another object is to provide means for 25 automatically locking the winding mechanism of the main spring while the alarm lever is in its "off" position, and means for releasing said locking means when the alarm lever is turned to its "on" position.

30 And another object is to provide means for automatically locking the winding mechanism of the main spring when the alarm spring is partly run down, and means for releasing said locking means when the 35 alarm spring is substantially wound up.

And a further object is to provide means for automatically actuating the alarm mechanism to induce ringing of the alarm when the main spring is substantially run down, 40 and whether the mechanism is in its "on" or "off" position.

These objects and other objects and advantages are attained with the use of my 45 invention, as will become apparent from the following description taken together with the accompanying drawings, in which,

Fig. 1 is an outer rear elevation of an alarm clock, to the inner mechanism of which my invention is applied;

50 Fig. 2 is an elevational view of said clock with the rear cover removed, showing the alarm lever in its "off" position, and as a consequence the winding mechanism of the main spring locked and the alarm setting mechanism likewise locked;

55 Fig. 3 shows the alarm spring partly

run down and the winding mechanism of the main spring locked as a consequence thereof, although the alarm lever is in its "on" position and the alarm setting mechanism is released;

Fig. 4 shows the alarm lever in "off" position, similarly as in Fig. 2, with the alarm setting mechanism and the main spring winding mechanism locked, and in addition 65 shows the main spring run down and as a consequence the spring arm which locks and releases the alarm operating mechanism has been forced to its release position thereby permitting the alarm to operate, as further 70 shown in Fig. 6, in dotted lines;

Fig. 5 is a detailed section on line 5—5 of Fig. 6, showing the gear means for actuating the spring arm which locks and releases the alarm operating mechanism; 75

Fig. 6 is a cross section on line 6—6 of Fig. 2, showing in full lines the spring arm and the alarm operating mechanism in shut-off position, similarly as in Fig. 2, and showing in dotted lines said spring arm and alarm operating mechanism in the release 80 position for effecting ringing of the alarm, as a consequence of the run-down main spring;

Fig. 7 is a detailed section taken on line 85 7—7 of Fig. 2;

Fig. 8 is a detailed section taken on line 8—8 of Fig. 3, and

Fig. 9 is a detailed section taken on line 90 9—9 of Fig. 8.

In the drawings I have shown my invention applied to an alarm clock of well-known construction, which has a casing 14 with a removable cover 15 and a frame 16 for mounting the various mechanisms of 95 the clock in the casing. Said mechanism includes as usual an alarm setting shaft 17 with a knob 18; also an alarm spring 19 on a winding shaft 20 having a handle 21, and the usual intermediate gearing which 100 drive the escapement pawl 22 for operating the shaft 23 with the arm 24 and hammer 25 of the alarm; said clock also containing a main spring 26 on a winding shaft 27 carrying a handle 28 and a gear 29 which 105 actuates the usual sets of gears and the time shaft 30 for operating the hour and minute hands (not shown).

In connection with the above type of alarm clock I have illustrated the preferred 110 form of construction for carrying my invention into effect, and this construction

comprises means for automatically locking the alarm setting and timing mechanism while the alarm lever is in its "off" position, and also means for releasing said locking means by the moving of said lever to its "on" position. This means includes a ratchet gear 32 fastened on the alarm setting shaft 17, and a pawl 33 pivoted on frame 16, which is automatically pressed against said gear by an arm 10 of a spring 34 to hold said shaft 17 locked while the alarm lever is in its "off" position, said spring 17 being mounted on a supporting post of the frame. The means for releasing said locking means includes a combination 15 alarm and locking lever 35 which takes the place of the usual alarm lever, and is pivoted at 36 on frame 16, and provided with an operating finger 35' extending through the usual slot in cover 15 to move the lever to 20 "on" and "off" position. An arm 38 extends from said lever and with its downturned end 39 engages pawl 33 to release it from gear 32 when lever 35 is moved to "on" position. This construction assures the moving 25 of the alarm lever 35 to "on" position before the alarm setting and timing mechanism associated with shaft 17 can be moved or set.

Means is provided for automatically locking the winding mechanism of the main spring while the alarm lever is in its "off" position, and for releasing said locking means for moving the lever to "on" position. The automatic locking means includes a 30 ratchet gear 40 fastened on main spring shaft 27, and a pawl 41 pivoted on frame 16 and being automatically pressed against said gear by a second arm 42 of spring 34, to hold said gear and shaft stationary and 35 prevent winding of the main spring. The releasing means includes an arm 43 on the inner end of lever 35, which engages a lug 44 on pawl 41 to release said pawl from the ratchet and permit the turning of the shaft 40 27 and thereby the winding of the main spring 26 when the alarm lever 35 is moved to "on" position. This construction assures 45 that the alarm lever will be turned to "on" position before the main spring can be wound, and thus remedies the frequent trouble of winding up the clock but forgetting to turn on the alarm before retiring.

I, furthermore, provide means for automatically locking the winding mechanism of the main spring to prevent winding thereof when the alarm spring is partly run down. This means includes a pinion 45 fastened on the winding shaft 20 of the alarm spring, and a gear 46 driven thereby; also a lever 60 47 pivoted on frame 16 at 48 and having a pawl 49, preferably integral therewith, for engaging ratchet 40 on shaft 27; a spring 50 engaging a lug 51 on said lever to automatically retain the pawl in locking position on the ratchet, and to prevent wind-

ing the main spring while the alarm spring is partly run down, as best shown in Fig. 3. A pin 52 on gear 46 travels with said gear when the alarm spring 19 and shaft 20 move, said pin engaging a curved part 53 70 on lever 47 thus raising said part of the lever and releasing pawl 49 from ratchet 40 when the alarm spring 19 has been substantially wound up, as best shown in Fig. 2, a pin 54 extending beneath wheel 46 and engaging a lug 55 on frame 16 to limit the rotation of said gear and to prevent pin 52 from moving beyond elbow 53' or from dropping the lever 47. This construction overcomes the frequent mistake of winding the 75 main spring of the clock without winding the alarm spring which may be entirely or partly run down, thereby leaving the alarm mechanism substantially inoperative, as the party retires.

Means is also provided for operating the alarm mechanism when the main spring is substantially run down, and the alarm mechanism will be rendered operative by said means whether the alarm lever and setting mechanism is in its "on" position or in its "off" position. This means includes a rod 57 bent transversely, then forwardly and downwardly from shaft 23 and being normally held stationary by having its free end 57' engaged by the bent end 58 of a spring arm 59 which is fastened on the forward part 16' of frame 16, as best shown in Fig. 9, to prevent operation of the alarm hammer 25. Said spring arm 59 is arranged to normally assume the release position, away from frame part 16', as shown in full lines in Fig. 9 and in dotted lines in Fig. 6, and when the alarm lever 35 is turned to "on" position (see also Figs. 3 and 8); and said spring arm is turned to locking position, as shown in dotted lines in Fig. 9, and in full lines in Fig. 6, when said lever 35 is moved to "off" position, said spring arm being drawn toward the frame by means of a toe 60 of shaft 61 which has a bevelled head 62 actuated by a cam portion 63 formed on lever 35; and said shaft is returned to release position by a spring 64 mounted on said shaft between a collar 65 and the frame. When the alarm setting lever 35 is placed in "on" position, the shaft 61 is moved by spring 64 to the position shown in Figs. 8 and 9, permitting spring arm 59 to assume its normal position, thereby freeing end 57' of rod 57, as shown in Fig. 9, permitting the alarm to ring; provided the gear 66 on alarm setting shaft 17 has been rotated, by the usual running gears of the clock connected thereto, until its notch 67 registers with finger 17' on shaft 17 thereby permitting said gear to drop and also release spring arm 59.

The particular means for operating the above alarm mechanism when the main

spring is run down, and whether the alarm lever 17 is in its "on" or its "off" position, includes a bell crank lever 68 fulcrumed on the frame, which with its arm 69 engages 5 and draws forward the spring arm 59 into the position shown in dotted lines in Fig. 6, thereby freeing spring finger 58 from end 57' of alarm rod 57, thus permitting the alarm to ring, even though shaft 61 with 10 its toe 60 and cam 62 have been turned backward to the locking position by cam 63 on lever 35 moved to its "off" position, as indicated in Fig. 6. A link 70 connects lever 68 with one arm of a bell crank 71 fulcrumed on a corner post 72 of frame 16, the 15 nut 72' of said post acting as a stop for lever 47; the other arm 73 is engaged by an arm 74 extending forward from the pawl end of lever 47, said lever arm 74 and bell crank 20 being actuated by a pin 75 on a gear 76 which is driven through an idler having a pinion 77 and attached gear 78 driven by a pinion 79 on main spring shaft 27. Thus when the main spring is substantially run 25 down, as best shown in Figs. 4 and 5, the main spring pinion 79 on shaft 27 will have moved the idler gear and pinion 78 and 77, and gear 76 with its pin 75 to swing arm 74 with its lever 47 and pawl 49, thereby 30 permitting partial winding of the main spring, and the subsequent winding of the alarm spring; and will also have moved arm 73 of bell crank 72 with the link 70, and bell crank lever 68 and thereby the spring arm 35 58 to its release position thus releasing the alarm rod 57, and thereby setting the alarm mechanism in operation, and this is effected whether the alarm lever and connections are in the "on" or the "off" position.

40 While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

50 Having described my invention, what I claim as new and desire to secure by Letters Patent is:

1. In an alarm clock having alarm setting mechanism and a shut-off lever, means for preventing the setting of said alarm while said lever is in shut-off position.
2. In an alarm clock having an alarm setting and timing mechanism and a shut-off lever, and means operated by said lever for locking the alarm setting mechanism while said lever is in its shut-off position.
3. In an alarm clock having alarm setting mechanism and a shut-off lever, means for automatically locking said setting mechanism, and means operated by said lever for

releasing said locking mechanism when the lever is moved to its "on" position.

4. In an alarm clock having an alarm setting shaft and a shut-off lever, spring pressed pawl and ratchet means connected to said shaft for automatically locking it while said lever is in its "off" position, and means on said lever for releasing said pawl when the lever is moved to its "on" position.

5. In an alarm clock having a shut-off lever, means for locking the main spring winding mechanism of said clock while said lever is in its shut-off position.

6. In an alarm clock having a shut-off lever, means connected with said lever for locking the winding mechanism of the main spring while the lever is in its "off" position and for releasing said locking means while the lever is in its "on" position.

7. In an alarm clock having a shut-off lever, means for automatically locking the main spring winding mechanism while said lever is in its "off" position, and means on said lever to engage and release said locking means when said lever is moved to its "on" position.

8. In an alarm clock having a main spring winding shaft and a shut-off lever, spring pressed pawl and ratchet means connected with said shaft for automatically locking the same, and means on said lever for engaging and releasing said locking means while the lever is in its "on" position.

9. In an alarm clock having a main spring winding shaft and a shut-off lever, a ratchet on said shaft and a spring pressed pawl for engaging said ratchet to prevent winding of the spring, while the said lever is in its "off" position, and an arm on said lever to engage said pawl and release it from said ratchet when the lever is turned to its "on" position.

10. In an alarm clock having a main spring winding mechanism, alarm setting mechanism, and a shut-off lever; means for locking said winding mechanism and setting mechanism, and means on said lever for releasing both of said locking means.

11. In an alarm clock having main spring winding mechanism and alarm setting mechanism; spring pressed means for automatically locking said winding mechanism and setting mechanism, and an alarm shut-off lever having means thereon for engaging and releasing both of said locking means.

12. In an alarm clock having a main spring winding shaft and an alarm setting shaft; pawl and ratchet means on each of said shafts and actuated by a spring for automatically locking said shafts, and a combination lever acting as an alarm shut-off lever and having arms for engaging and releasing said locking mechanisms when said lever is turned to its "on" position.

13. In an alarm clock having an alarm spring and a main spring and winding mech-

- anism therefor, means for automatically locking the winding mechanism of the main spring when the alarm spring is partly run down.
5. In an alarm clock having an alarm spring and a main spring and winding mechanism therefor, means for automatically locking the main spring, and means for releasing said locking means when the 10 alarm spring has been substantially wound up.
15. In an alarm clock having an alarm spring and a main spring with a winding shaft, a lever with means for engaging means on said shaft to prevent winding of the main spring, and means actuated by the alarm spring for moving said lever to permit winding of the main spring.
20. In an alarm clock having an alarm spring and a main spring and a winding shaft for each spring, a member on the main spring shaft, means with an arm for automatically engaging said member to lock said main spring shaft, and gear means connected with the alarm spring shaft for actuating said means.
25. In an alarm clock having an alarm spring with a shaft and a main spring with a shaft, a ratchet on the main spring shaft, a spring pressed lever with a pawl arm to automatically engage said ratchet and lock its shaft in position, gear means connected with the alarm spring shaft and including an element to actuate said lever and release its pawl from said ratchet when the alarm spring is substantially wound up.
30. In an alarm clock having a main spring with a winding shaft and an alarm spring with a shut-off lever, a ratchet on the main spring shaft, spring pressed means for automatically engaging and locking said ratchet when said lever is in "off" position, means automatically engaging and locking said ratchet and its shaft when the alarm 35 is partly run down, means actuated by the alarm lever when moved to its "on" position for releasing one of said ratchet engaging means and means actuated by the winding of said alarm spring for releasing the other of said ratchet engaging means.
40. In an alarm clock having a main spring and alarm ringing mechanism with setting means, means for retaining said alarm ringing mechanism inoperative, means for normally releasing said retaining means at the time set by said setting means, and means actuated by the main spring when it is substantially run down for releasing said retaining means to render the alarm 45 ringing mechanism operative, whether said setting means is in its "off" or in its "on" position.
50. In an alarm clock having a main spring and an alarm mechanism with means including a spring arm for shutting off said
- alarm, means including a bell crank lever for releasing said shut off means, and means actuated by the main spring when it is substantially run down for operating said lever and arm to effect ringing of the alarm. 70
55. In an alarm clock having a main spring and an alarm mechanism with a lever and means for shutting off said alarm, means for releasing said shut-off means when said lever is in the shut-off position, and means actuated by the main spring when it is substantially run down for operating said releasing means to effect ringing of the alarm. 75
60. In an alarm clock, alarm ringing means, means for holding said alarm ringing means inoperative, a main spring shaft and gear means connected therewith, and link and lever means actuated by said gear means when said main spring is substantially run down for removing said holding means from said alarm ringing means. 80
65. In an alarm clock, alarm ringing means with a rod, a spring arm for normally holding said rod and means inoperative, a member for withdrawing said spring arm from said rod, a link connected to said member, a main spring shaft and pinion, and gear means actuated by said pinion for operating said link to release said ringing means when the main spring is substantially unwound. 85
70. In an alarm clock, alarm ringing means with a rod, a spring arm for normally holding said rod and means inoperative, a member for withdrawing said spring arm from said rod, a link connected to said member, a main spring shaft and pinion, and gear means actuated by said pinion for operating said link to release said ringing means when the main spring is substantially unwound. 90
75. In an alarm clock, alarm ringing means with a rod, a spring arm for normally holding said rod and means inoperative, a member for withdrawing said spring arm from said rod, a link connected to said member, a main spring shaft and pinion, and gear means actuated by said pinion for operating said link to release said ringing means when the main spring is substantially unwound. 95
80. In an alarm clock, alarm ringing means, a spring arm, an alarm lever with means for moving said spring arm to shut off said ringing means, a member for withdrawing said spring arm to permit operation of said ringing means, a main spring shaft, and means actuated by said main spring shaft for operating said member when the main spring is substantially run down for releasing said alarm ringing means to effect ringing thereof while the alarm lever is in shut-off position. 100
85. In an alarm clock, alarm ringing means, a spring arm, an alarm lever with means for moving said spring arm to retain said ringing means inoperative, a bell crank lever for withdrawing said spring arm to effect operation of said ringing means, a main spring shaft with a pinion, gear means actuated by said pinion, a bell crank lever connected to the first said bell crank lever, and means on said gear means for operating said bell crank levers to withdraw said 105 spring arm from the ringing means. 110
90. In an alarm clock, alarm ringing means, a spring arm, an alarm lever with means for moving said spring arm to retain said ringing means inoperative, a bell crank lever for withdrawing said spring arm to effect operation of said ringing means, a main spring shaft with a pinion, gear means actuated by said pinion, a bell crank lever connected to the first said bell crank lever, and means on said gear means for operating said bell crank levers to withdraw said 115 spring arm from the ringing means. 120
95. In an alarm clock having a main spring with a shaft and an alarm mechanism with ringing means and setting means therefor, means for locking said main spring, means for locking said alarm ringing means, means for locking said alarm setting means, and a shut-off lever with means thereon for simultaneously releasing all of said locking means. 125
100. In an alarm clock having a main spring with a shaft and an alarm mechanism with ringing means and setting means therefor, means for locking said main spring, means for locking said alarm ringing means, means for locking said alarm setting means, and a shut-off lever with means thereon for simultaneously releasing all of said locking means. 130

27. In an alarm clock having a main spring with a shaft and an alarm mechanism with ringing means and time setting means with a shaft; means for automatically locking said main spring shaft, means for automatically locking said alarm setting shaft, means for locking said alarm ringing means, and a combination shut-off lever with means thereon for simultaneously releasing all of 5 member when said alarm spring is wound up, an arm on said pawl member, and means actuated by said main spring for engaging said arm and therewith releasing said pawl from the main spring and shaft and also 45 actuating said member to move said spring arm and render the ringing means effective when the main spring is substantially run down.
- 10 28. An alarm clock comprising in combination, an alarm mechanism with a spring and ringing means actuated thereby, a spring arm, an alarm lever with means for moving said spring arm to shut off said ringing means, a crank member for engaging 50 and withdrawing said spring arm to permit operation of said ringing means, a bell crank lever connected therewith, a main spring with a shaft, means including a lever and pawl for locking said main spring shaft 55 when the alarm spring is partly run down, means actuated by said alarm spring for releasing said lever and pawl when said alarm spring is wound up, an arm on said pawl, and gear means with a pin driven by said main spring and shaft for engaging and moving said arm and thereby releasing said pawl from the main spring shaft, said arm also engaging and moving said bell crank lever to withdraw said crank member to release said ringing means when the main spring is substantially run down.
- 15 29. An alarm clock comprising in combination, an alarm mechanism with ringing means, a spring arm, an alarm lever with means for moving said spring arm to shut-off said ringing means, a member for engaging 60 and withdrawing said spring arm to permit operation of said ringing means, a main spring with a shaft, an alarm spring, means including a pawl member for locking said main spring and shaft, means actuated by 65 said alarm spring for releasing said pawl
- 20 25 30 35 40
29. An alarm clock comprising in combination, an alarm mechanism with ringing means, a spring arm, an alarm lever with means for moving said spring arm to shut-off said ringing means, a member for engaging and withdrawing said spring arm to permit operation of said ringing means, a main spring with a shaft, an alarm spring, means including a pawl member for locking said main spring and shaft, means actuated by said alarm spring for releasing said pawl
30. An alarm clock comprising in combination, an alarm mechanism with a spring and ringing means actuated thereby, a spring arm, an alarm lever with means for moving said spring arm to shut off said ringing means, a crank member for engaging 70 and withdrawing said spring arm to permit operation of said ringing means, a bell crank lever connected therewith, a main spring with a shaft, means including a lever and pawl for locking said main spring shaft when the alarm spring is partly run down, means actuated by said alarm spring for releasing said lever and pawl when said alarm spring is wound up, an arm on said pawl, and gear means with a pin driven by said main spring and shaft for engaging and moving said arm and thereby releasing said pawl from the main spring shaft, said arm also engaging and moving said bell crank lever to withdraw said crank member to release said ringing means when the main spring is substantially run down.
- In testimony whereof I have signed my name to this specification in the presence of two subscribing witnesses.
